UNITED STATES PATENT OFFICE

MICHAEL L. SULLIVAN, OF OXNARD, CALIFORNIA

UNIVERSAL CONNECTION BETWEEN HEADWALL AND DRAINPIPE

Application filed August 13, 1930. Serial No. 474,953.

This invention relates to culverts, and more especially to an improved type of headwall for conduits of that general class.

An object of the invention is the provision of a headwall for a culvert, and means for connecting the culvert to the headwall whereby the culvert extends therefrom at an angle other than a right angle, thereby permitting the headwall to be disposed in a vertical plane, and the culvert to slope either upwards or downwards therefrom, and/or at an oblique angle measured in a horizontal plane.

Another object is to so form the coupling means that it is adjustable, thereby providing a universal coupling which is readily variable to permit the culvert to extend at any desired degree of angularity and at any desired direction from the headwall, so as to meet any particular set of circumstances of installation.

Another object is to provide a universal coupling for a culvert, of the general class described, which is particularly adapted though not necessarily limited to use in conjunction with a headwall of the type disclosed in Patent No. 1,760,380, issued to me on May 27th, 1930.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a side elevation of a pair of sidewalls of the present invention, with a culvert extending therebetween as in actual service.

Fig. 2 is a rear view of one of the headwalls. This view may be considered as a vertical sectional view taken upon the line 2—2 of Fig. 1, with the direction of view as indicated, this view having been taken without the earth of the roadway disposed about the culvert.

Fig. 3 is a longitudinal, vertical sectional view of the headwalls and culvert arranged angularly.

The device of the present invention repre-

sents an improvement over the headwall disclosed in Patent #1,760,380, issued to me on May 27th, 1930, although it should be explained that the universal coupling of the present invention might also be applied to other forms of headwalls without departing from the spirit and scope of the present invention.

One of the universal couplings 6 of the present invention, is intended to be used to connect each end of a conduit such as a culvert 7, to a headwall 8. Such arrangement of a culvert 7 and headwall 8, is commonly employed to provide a water course under a roadway 9, so as to prevent washing of the roadway 9 under storm conditions. As herein shown and described, each of the headwalls 8 is similar to the headwall disclosed in my aforesaid patent, comprising a sheet 11 of suitable material, preferably galvanized iron, and comprising an upstanding portion 12 preferably corrugated, with the top and bottom edges bent into horizontal planes to provide top and bottom portions 13 and 14 respectively, of the headwall. Rigidity is imparted to each headwall by a pair of spaced angle irons 16 riveted or otherwise attached to the back side of the upstanding portion 11, and suitable gusset plates 17, preferably having peripheral flanges 18, are interposed between the upstanding portion 11 and the horizontal portions 13 and 14 of the headwall 8. The extreme edges 19 of the top and bottom 13 and 14 are introverted, thus providing flanges adapted to engage the earth 21 or other material within which the culvert 7 is embedded.

An aperture 22 is formed in the upstanding portion 11 of the headwall 8, preferably substantially centrally thereof; and a relatively short tube 23 is made fast to the upstanding portion 11 in communication with the aperture 22. Moreover, that end of the tube 23 which is associated with the upstanding portion 11, is preferably tightly connected thereto, so as to prevent any possibility of leakage therebetween—all liquid passing through the tube 23 thus being conveyed through the headwall also, with the result that the earth 21 filling the space between the

two headwalls, will not be washed out due to any leakage from the culvert 7.

An enlarged portion 24 is formed on the inner end of the tube 23. This enlarged portion may be formed of sheet metal either integral with or attached to the material of which the tube 23 is formed; or the enlargement 24 may be in the form of a casting fitted upon the inner end of the tube 23. The enlargement 24 is spherical, or more precisely, the exterior surface thereof, has the configuration of a spherical zone. Moreover, a plane taken through the spherical surface of the enlargement 24 in parallelism with, and as close as possible to the plane of the upstanding portion 11 of the headwall, does not represent a true equatorial plane of the sphere of which the enlargement 24 represents a zone. A diameter of the enlargement 24 measured in this plane, will not be as great as a diameter measured in a plane at a slightly greater distance from the plane of the upstanding portion 11. In other words, the curvature of the outside surface of the enlargement 24, has been carried past its portion of greatest diameter measured perpendicularly to the axis of the tube 23, so that the portion of the enlargement 24 which is proximal to the upstanding portion 11 is of slightly reduced size. This permits an enlarged portion 26 which is formed on an end of a second tube 27, to be engaged upon the spherical portion 24 of the tube 23, in such a manner that the tube 27 can not be removed from the tube 23 without expanding the enlargement 26. Moreover, the enlargement 26 may be left sufficiently loose upon the enlargement 24, to permit universal adjustment of the tube 27 with respect to the tube 23 whereby the tube 27 extends at any selected degree of angularity with respect to the plane of the upstanding portion 11 of the headwall.

The tube 27 and its enlargement 26 are split longitudinally into sections 28 and 29, each of which is preferably slightly more than a semi-circle in cross-sectional configuration, with the result that their longitudinal edges overlap as best shown upon Fig. 2. An angle iron 31 extends longitudinally of each section 28, 29 adjacent each longitudinal edge thereof, thus providing flanges 32 which extend radially therefrom. A plurality of bolts 33 extend between associated flanges 32 of both sections 28, 29, so that when the nuts 34 thereof are tightened, the sections 28 and 29 are drawn firmly together. When the bolts 33 associated with the enlargement 26 are tightened, this enlargement will be clamped tightly against the spherical surface of the enlargement 24 so as to rigidly retain the tube 27 in selected degree of angularity with the plane of the upstanding portion 11 of the headwall.

The tube 27 is adapted to receive an end of the culvert 7, and inasmuch as these cul-

verts are usually corrugated, I prefer to form the tube 27 complementarily thereto, although it would be entirely within the scope of the present invention to omit the corrugations thereof. After insertion of an end of the culvert 7 into the tube 27, the bolts 33 at that end of the tube 27 remote from its enlargement 26, may be tightened, thus firmly clamping the sections 28 and 29 upon the culvert 7.

In road construction, it frequently occurs in the installation of a storm drain, that one or both of the headwalls therefor, should be disposed vertically whereas the culvert extending therebetween, slopes at a material angle with respect to the horizontal. As will be readily apparent, such construction may very easily be attained by means of the universal coupling of the present invention whereby the culvert 7 may be attached to either or both headwalls 8 at any selected degree of angularity therewith. Obviously, the universal coupling 6 also permits variation of the horizontal angle between the culvert 7 and the headwall, with the result that the improved headwall of the present invention makes it possible to meet substantially any circumstances of installation.

It is to be understood that the details of the invention as herein disclosed, are subject to alteration within the spirit or scope of the appended claims.

I claim:

1. In combination, a culvert, a headwall therefor comprising an apertured wall, and means for coupling said culvert to said wall said means enabling adjustment of said culvert with respect to said headwall to vary the angle therebetween.

2. In combination, a culvert, a headwall therefor, and means for coupling said culvert to said headwall, said coupling means being adjustable to vary the angularity of said culvert with respect to said headwall.

3. In combination, a culvert, a headwall therefor, and means for coupling said culvert to said headwall, said coupling means being universally adjustable to vary the angularity of said culvert with respect to said headwall.

4. A headwall for a culvert, comprising an apertured wall, a tube adjustably carried by said wall with its bore communicating with the aperture in said wall, the end of said tube remote from said wall being split into sections, and means for clamping a culvert between said sections.

5. A headwall for a culvert, comprising an apertured wall, a tube carried by said wall with its bore communicating with the aperture in said wall, said tube being adjustable to vary its angularity with respect to said wall.

6. A headwall for a culvert, comprising an apertured wall, a tube carried by said wall with its bore communicating with the aper-

ture in said wall, said tube being universally adjustable to vary its angularity with respect to said wall.

7. In combination, a culvert, an apertured headwall therefor, and a universal coupling comprising a tube rigid with said headwall and communicating with the aperture therein, a spherical enlargement on said tube, a second tube having a spherical enlargement 10 adjustably engaging that of the rigid tube, and means for securing said culvert to said second tube.

8. In combination, a culvert, an apertured headwall therefor, and a universal coupling 15 comprising a tube rigid with said headwall and communicating with the aperture therein, a spherical enlargement on said tube, a second tube having a spherical enlargement adjustably engaging that of the rigid tube, 20 means for rigidly clamping said tubes in selected degree of angularity with each other, and means for securing said culvert to said second tube.

9. In combination, a culvert, an apertured headwall therefor, and a universal coupling 25 comprising a tube rigid with said headwall and communicating with the aperture therein, a spherical enlargement on said tube, a second tube having a spherical enlargement 30 adjustably engaging that of the rigid tube, said second tube and its enlargement being split longitudinally into two sections, and means for clamping said sections together with an end of said culvert received therebetween.

10. In combination, a culvert, an apertured headwall therefor, and a universal coupling 40 comprising a tube rigid with said headwall and communicating with the aperture therein, a spherical enlargement on said tube, a second tube having a spherical enlargement 45 adjustably engaging that of the rigid tube, said second tube and its enlargement being split longitudinally into two sections, an end of said culvert being receivable between said sections, and means for clamping said sections together upon said culvert and for tightening the enlarged portion of said split tube upon that of said rigid tube.

11. In combination, a culvert, an apertured headwall therefor, and a universal coupling 50 comprising a tube rigid with said headwall and communicating with the aperture therein, a spherical enlargement, on said tube, a second tube having a spherical enlargement 55 adjustably engaging that of the rigid tube, said second tube and its enlargement being split longitudinally into two sections, an end of said culvert being receivable between said sections, a flange extending longitudinally of each of said sections adjacent each edge thereof, and means engaging associated flanges of both sections for drawing them toward each other to clamp said sections upon said culvert and to tighten the enlarged

portion of said split tube upon that of said tube.

In testimony whereof I have signed my name to this specification.
